CLAIM

The ornamental design for a recycling bin, as shown and described.

DESCRIPTION

FIG. 1 is a perspective view of a first embodiment of the recycling bin, illustrating my new design;

FIG. 2 is a front elevational view of the recycling bin of FIG. 1;

FIG. 3 is a side elevational view of the recycling bin of FIG. 1;

FIG. 4 is a rear elevational view of the recycling bin of FIG. 1;

FIG. 5 is a top plan view of the recycling bin of FIG. 1;

FIG. 6 is a bottom plan view of the recycling bin of FIG. 1;

FIG. 7 is a perspective view of a second embodiment of the recycling bin, illustrating my new design;

FIG. 8 is a front elevational view of the recycling bin of FIG. 7;

FIG. 9 is a top plan view of the recycling bin of FIG. 7;

FIG. 10 is a bottom plan view of the recycling bin of FIG. 7; and,

FIG. 11 is a rear elevational view of the recycling bin of FIG. 7.

FIG. 1FIG. 2FIG. 3FIG. 4

FIG. 5

FIG. 6

FIG. 10

FIG. 7

FIG. 9

FIG. 8

FIG.11
